UNITED STATES PATENT OFFICE

CHARLES W. COONEY, OF WAUKEGAN, ILLINOIS

GRAVE FORM

Application filed October 26, 1925. Serial No. 64,765.

My invention is concerned with grave forms, which are designed to improve the appearance of the individual graves to which they are applied, and which when employed generally in a cemetery produce a degree of similarity that will enhance the effect of the cemetery as a whole. To this end it consists of a preferably rectangular form that covers the grave proper, the inside being open so that flowers or turf may be planted therein, and the whole surmounted with a perforated pipe so that the interior and the immediately surrounding area may be expeditiously and easily watered whenever it may be found necessary.

To illustrate my invention, I annex here-to a sheet of drawings in which the same reference characters are used to designate identical parts in all the figures, of which—

20 Fig. 1 is a perspective view of my invention in place on a grave and with a headstone placed therein;

Fig. 2 is a top plan view of one end of the same;

25 Fig. 3 is an inverted plan view of one end thereof;

Fig. 4 is an end elevation;

Fig. 5 is a side elevation with one end in central vertical section;

30 Fig. 6 is a horizontal section of one corner through the sprinkling pipe; and

Fig. 7 is a perspective view of an elbow connection employed at each corner.

For convenience of transportation, I preferably construct my novel form in two side and two end sections, each section having the same design in vertical cross section, and having similar mitered ends so that the two side and end sections may be brought together and secured to produce the complete rectangular form with the open center. The sections may be constructed of sheet metal or a casting, or might be formed of concrete or any suitable material having the necessary wearing qualities so that it will stand exposure to the weather. I have illustrated it as formed of sheet metal, and each section is preferably formed from a single piece of sheet metal, and is constructed as follows: At the bottom, I form the vertical downwardly pro-

jecting flange 10, which I may call the anchoring member, since it is in use embedded in the ground so as to prevent any lateral shifting or displacement of the completed form. Above this anchor member 10 and extending horizontally at right angles thereto is what I may call the positioning member 11, which is substantially wider than the anchoring member so as to furnish a solid support for the completed form on the ground over which it is placed. On the outer edge of the positioning member is turned up the side member 12, which for the ornamental effect is preferably curved in the arc of a circle, as shown. This side member 12 is surmounted by the sprinkling tube 13, which might be formed separately, but which I preferably form from the sheet metal by bending the edge into the shape shown and soldering or welding the meeting surfaces. On the interior, and preferably at the center of the tube, I form the series of perforations 14 which, when the pipe is filled with water under pressure, causes a discharge of water sufficient to cover the entire interior area of the form. On the outer side of the tube I form a similar series of perforations 15, which serve to water the verdure for some distance on the outside of the form. To secure the various sections together, I bent horizontally from the end of either the positioning member 11 or the side member 12 the vertical flange 16, which will have a plurality of perforations 17 therein, which will be in register with the perforations of the adjacent member when the parts of the form are assembled, so that short bolts 18 may be passed therethrough and the parts drawn together by nuts in a manner that will be readily apparent. To secure substantially water tight joints in the meeting ends of the tube sections 13, I place in said meeting sections the soft metal elbows 19, which have the diagonal enlargement 20 across the center so that when they are inserted in the ends of the tubes and are drawn together by the bolts 18 the enlargement will be crushed together between the adjacent ends of the pipe sections to form a substantially liquid proof joint. The sections are further preferably

secured together by providing the plates 21 having the four bolt holes therein adapted to register with corresponding bolt holes formed in the end portions of the positioning members 11, so that by application of the bolts 22 the rigidity of the structure is increased. Threaded into an opening formed in the under side of one of the end pipes 13 is a vertical pipe 23 which may extend down through an opening 24 formed in the horizontal positioning member 11, where it is connected by the elbow 25 with a pipe 26 which leads to a convenient water pipe with which the cemeteries will be supplied. A valve will be placed in the pipe 26, and whenever the grave needs watering, all that is necessary is to open the valve for the required length of time.

I contemplate painting the form green, and as nearly the color of the grass as is possible, thereby enhancing the effect of the verdure. A headstone 27 may of course be placed in the form if desired.

While I have shown and described my invention as embodied in the form which I at present consider best adapted to carry out its purposes, it will be understood that it is capable of modifications, and I do not desire to be limited in the interpretation of the following claims except as may be necessitated by the state of the prior art.

What I claim as new and desire to secure by Letters Patent of the United States, is—

1. A grave form comprising a frame having a downwardly projecting anchoring member at its bottom, a horizontal positioning member extending therefrom, a side member extending upward from the positioning member, said frame being made up of the plurality of side and end sections having mitered ends which may be secured together to produce a rectangular form when the parts are assembled at the grave.

2. A grave form comprising a frame having a downwardly projecting anchoring member at its bottom from which extends a horizontal positioning member, which is surmounted by a side member, on the upper edge of which is secured a perforated pipe, said frame being made up of a plurality of side and end sections having mitered ends which may be secured together to produce a rectangular form when the parts are assembled at the grave, the pipe sections being connected by metal elbows adapted to be secured inside the adjacent ends thereof before the sections are finally secured together.

3. A grave form composed of sections comprising anchoring members at the bottom, horizontal positioning members above the anchoring members, side members above the positioning members, tubes surmounting the side members, said sections having mitered ends with vertical flanges thereon having registering apertures therein so that they may

be bolted together to form a rigid structure, and soft metal elbows having mitered enlargements adapted to be crushed between adjacent mitered ends of tubes as they are drawn together by the bolts in assembling the device.

4. A grave form comprising an oblong form surmounted by a perforated pipe appearing as part of the frame and extending around the same, but small in cross section as compared to that of the frame, said frame being made up of four sections having co-operating mitered ends, each section being provided with means co-operating with the ground to hold it from either vertical or horizontal displacement relative to the surface thereof.

5. A grave form comprising a frame having a downwardly projecting anchoring member at its bottom adapted to penetrate the ground, a horizontal positioning member extending therefrom adapted to rest on the ground, a side member rising from the horizontal member, and a perforated pipe attached directly to the top of the side member.

In witness whereof, I have hereunto set my hand this 14th day of October, 1925.

CHARLES W. COONEY.
